UNITED STATES PATENT OFFICE.

AUGUST KEHM, OF CHICAGO, ILLINOIS.

DESIGN FOR A RADIATOR.

58,189.

Specification for Design.

Patented June 21, 1921.

Application filed March 12, 1917. Serial No. 154,413. Term of patent 3½ years.

To all whom it may concern:

Be it known that I, AUGUST KEHM, a citizen of the United States, residing at Chicago, in the county of Cook and State of Illinois, have invented a new, original, and ornamental Design for Radiators, of which the following is a specification, reference being had to the accompanying drawing, forming a part thereof, wherein—

Figure 1 is a front elevation of the radiator,

Fig. 2 is a plan view of the same partly broken away and with the members thus exposed shown in section; and

Fig. 3 is an end elevation of the radiator.

The ornamental design here shown is also shown in my application for mechanical patent on radiator, Serial No. 154,349, filed March 12, 1917, wherein the improved construction of radiator is claimed as a separate invention.

I claim:

The ornamental design for a radiator as shown.

AUGUST KEHM.
